UNITED STATES PATENT OFFICE.

MAY F. TAYLOR AND EFFIE B. BAUMGARTNER, OF BOULDER, COLORADO.

DESIGN FOR A TWINE HOLDER.

Application filed April 26, 1926. Serial No. 17,463. Term of patent 7 years.

To all whom it may concern:

Be it known that we, MAY F. TAYLOR and EFFIE B. BAUMGARTNER, both citizens of the United States, and residents of Boulder, in the county of Boulder and State of Colorado, have invented a certain new, original, and ornamental Design for Twine Holders, of which the following is a specification, reference being had to the

accompanying drawing, forming a part hereof.

The drawing illustrates a perspective view of our new design for a twine holder.

We claim:

The ornamental design for a twine holder as shown.

MAY F. TAYLOR.

EFFIE B. BAUMGARTNER.
